FUSE LINK

Eugene F. Boothe, St. Louis, Mo., assignor to
 James R. Kearney Corporation, St. Louis, Mo.,
 a corporation of Missouri

Application May 25, 1936, Serial No. 81,636

4 Claims. (Cl. 200—117)

This invention relates generally to fuse links, and more specifically to fuse links of the tension type provided with strain-absorbing means for relieving the fusible elements of the link of tensile strains which would be otherwise imposed thereon, the predominant object of the invention being to provide a fuse link with strain-relieving means of such construction and arrangement that, while the unruptured fuse link is provided with great tensile strength, quick separation of parts of the fuse link on rupture of the fusible element thereof is not unduly interfered with by the strain-absorbing means.

Another extremely important object of the invention is to provide a fuse link which is so constructed and arranged that during a switching or lightning surge of current the improved fuse link is less likely to open than the conventional fuse link not constructed and arranged in accordance with this invention. This results from the fact that an arcing gap is provided in the fuse link structure between the strain-absorbing means and an adjacent portion of the fuse link structure, and when the surge passes through the fusible element of the fuse link structure there is a voltage drop across the arcing gap sufficient to cause the gap to break down and by-pass a portion of the current over the gap. The time duration involved is so small that the strain-absorbing means is not burned in two by the by-passed current, and hence the fuse link is not damaged by the surge current.

Fuse links of the type referred to above ordinarily are adapted to be held under mechanical tension produced either by spring means which form parts of the fuse link structures, or parts of the protective apparatus with which the fuse links are associated, the purpose being to create a wide gap between the severed ends of the fusible element of the fuse link after the same has become ruptured by passage of abnormal current, and to quickly extinguish any arc attending the blowing of the fusible element by causing the ruptured ends thereof to fly apart under the action of the spring tension.

A heretofore prevailing difficulty inherent in tension fuse links, particularly those of low or fractional ampere current carrying capacity, resulted from the tendency of the fusible element to become severed by reason of the mechanical forces applied thereto, or if not actually severed the application of such forces to the fusible element for a long period of time resulted in alteration of the operating characteristics, or rating, of the fuse link. In other words, it has been de-

termined that an unstressed fuse wire which is intended to become ruptured upon passage therethrough of, say, three-fourths of an ampere, when held under mechanical tension of the order produced by spring means found in the usual types of protective apparatus, is ruptured by currents of a magnitude substantially less than the figure specified.

The purpose of this invention, therefore, is to provide a fuse link construction which will not be harmfully affected by the application thereto of relatively high mechanical forces by relieving in an improved manner the fusible element of the improved fuse link structure of the forces produced by the tensioning means, and which is less likely to open during passage of a surge of current due to switching or lightning than were fuse links not constructed in accordance with this invention.

Fig. 1 is a view, partly in vertical section and partly in side elevation, of a fuse cartridge having the improved fuse link associated therewith.

Fig. 2 is a fragmentary view, partly in vertical section and partly in elevation, of a portion of the structure illustrated in Fig. 1, but viewing same from a different angle.

In the drawing, wherein is shown for the purpose of illustration, merely, one embodiment of the invention, A designates a fuse cartridge adjacent to the lower end of which a terminal member B is fixed, said terminal member B being adapted to aid in electrically associating the fuse cartridge A with a switch apparatus (not shown). At its upper end the fuse cartridge A has associated with it an adapter C which comprises a short tubular portion C^a that is extended downwardly into the tube A' of the fuse cartridge A, and an outstanding annular flange C^b which contacts with the top face of said tube.

The improved fuse link includes a contact head 1 which is fixedly located at the outer end of a strip 2 of conducting material which serves as a terminal member of the fuse link, said contact head being arranged in contact with the top face of the flange C^b of the adapter C, and said strip 2 being extended downwardly into the tube A' of the cartridge A. Extended upwardly through the cartridge tube A' is an electrical conductor 3, which serves as a terminal element of the fuse link, the end 3' of said conductor which is located within the tube A' being spaced a considerable distance from the inner or lower end of the strip 2. The opposite end portion of the conductor 3 is turned about the lower end of the fuse cartridge and is extended upwardly with respect thereto,

as indicated at 3^a in Fig. 1, said upwardly extended portion of said conductor being mechanically and electrically clamped to the terminal member B of the fuse cartridge through the instrumentality of a suitable clamping screw D.

The strip 2 and the conductor 3 are connected together by connecting means which includes a strain wire 4 that is extended through apertures 5' formed through a pair of blocks 5 formed of fiber or other suitable electrical insulating material. These blocks 5 are secured to the strip 2 at opposite side faces thereof by means of a rivet 6 or other suitable fastening means which passes through apertures formed through the blocks 5 and the strip 2 (see Fig. 1). The portion 4^a of the strain wire which extends through the apertures 5' of the blocks 5 may be described as a bridge portion, and extended from the opposite ends of this bridge portion are substantially parallel strain wire portions 4^b, end portions of which are arranged parallel and in contact with the adjacent end portion of the conductor 3. The end portions of the strain wire portions 4^b are secured to the conductor 3 by a sleeve 7 formed of conducting material which closely embraces the end portion of the conductor and the portions of the strain wire portions 4^b which contact therewith. As shown in Figs. 1 and 2, the sleeve 7, which by preference is formed of suitable metal, is flattened as is the end portion of the conductor 3, and therefore the end portions of the strain wire portions 4^b are very securely clamped to the conductor 3 by said flattened sleeve 7. In order to eliminate any chance that the tensional strains to which the strain wire 4 is subjected may result in the strain wire portions 4^b being pulled from between the sleeve 7 and the conductor 3, said portions 4^b are preferably bent double, as shown by dotted lines in Fig. 2, and also at bent ends 4^c of said strain wire portions 4^b, which extend slightly outside of the sleeve 7, soldered joints are produced which firmly secure the strain wire and the sleeve 7 together.

With regard to the strain wire 4, it is of extreme importance to note that a gap G (see Fig. 1) is present between the strain wire and the strip 2, and this gap takes the strain wire out of direct electrical connection with the strip 2 and under normal conditions prevents the strain wire from being a direct part of an electrical circuit of which the fuse link forms a part.

Secured by solder or otherwise at one end to the strip 2 and by solder or otherwise at the opposite end to the sleeve 7 is the fusible element 8 of the fuse link. As shown to the best advantage in Fig. 2, the fusible element 8 is out of direct electrical connection with the strain wire 4.

Extended downwardly from the strip 2 is an expulsion tube 9 formed of electrical insulating material which embraces the extreme lower portion of the strip 2, the lower ends of the blocks 5, the strain wire 4, the sleeve 7, a portion of the conductor 3, and a large part of the fusible element 8. The lower portion 2' of the strip 2 which extends into the expulsion tube is of reduced width, whereby said strip is provided with shoulders 2^a which contact with the upper edge of the expulsion tube. Extended upwardly into the expulsion tube 9 from a point a considerable distance below the lower edge of said expulsion tube is an elongated tubular element 10, which at its lower end is provided with an outstanding, annular flange 11, and an expansible coil spring 12 is interposed under compression between said annular flange of the tubular element 10 and the lower

edge of the expulsion tube 9. A button 13 is secured to the conductor 3, and this button holds the tubular element in its elevated position so that the coil spring 12 is maintained in compression.

In the use of the improved fuse link disclosed herein, the strain wire 4 is not in direct electrical contact with the strip 2 because of the presence of the gap G which separates the bridge portion 4^a of said strain wire from said strip, hence all electrical current conducted by the fuse link under normal operating conditions must flow through the fusible element 8. When a fault occurs in the line protected by the improved fuse link, the fusible element 8 melts and thereafter the current flows through the strain wire 4, said current passing from the end of the strip 2 to said strain wire in the form of an arc. The arc thus produced breaks the strain wire at the bridge portion 4^a thereof, allowing the separated ends of said bridge portion to be pulled out of the apertures 5' of the blocks 5 by the associated switch mechanism or by the coil spring 12, and thus permit the fuse link to separate. The importance of the gap G resides in the fact that a small fraction of an ampere through an arc will break a strain wire of the required strength, whereas, if the strain wire were continuous, several amperes would be required in order to melt the strain wire and break the circuit.

A further important advantage of the gap G is that during a surge of current through the improved fuse link due to switching or lightning, the fuse link is much less likely to open than a fuse link not provided with such a gap. This results from the fact that when the surge passes through the fusible element, for instance, 10,000 amperes in 3 or 4 micro-seconds, there is a voltage drop across the arcing gap G sufficient to cause the gap to break down and by-pass a portion of this current over the gap, and because the time duration of such by-passing of current is so small the strain wire is not burned in two and the fuse link is not damaged by the surge of current.

I claim:

1. A fuse link assembly including a pair of spaced terminal members, a fusible element for electrically connecting said terminal members, and connecting means for mechanically connecting said terminal members so as to relieve said fusible element of tension applied to the fuse link assembly, said connecting means including a strain wire connected to one of said terminal members and insulating means for connecting said strain wire to the other of said terminals in spaced relation with respect thereto, so as to provide a gap between said strain wire and said terminal, which electrically separates same during normal operation of the fuse link assembly and over which current passes during abnormal passage of current through the fuse link assembly, said insulating means including a block secured to said terminal member and provided with an aperture through which said strain wire passes so as to provide a portion of the strain wire which is disposed in spaced alignment with the adjacent terminal to produce said gap.

2. A fuse link assembly including a pair of spaced terminal members, a fusible element for electrically connecting said terminal members, and connecting means for mechanically connecting said terminal members so as to relieve said fusible element of tension applied to the fuse link assembly, said connecting means including a strain wire connected to one of said terminal

members and insulating means for connecting said strain wire to the other of said terminals in spaced relation with respect thereto, so as to provide a gap between said strain wire and said 5 terminal, which electrically separates same during normal operation of the fuse link assembly and over which current passes during abnormal passage of current through the fuse link assembly, said insulating means including a pair 10 of spaced blocks secured to said terminal member at opposite sides thereof and provided with apertures through which said strain wire passes so as to provide a portion of the strain wire which is disposed in spaced alinement with the adjacent terminal to produce said gap. 15

3. A fuse link assembly including a pair of spaced terminal members, a fusible element for electrically connecting said terminal members, and connecting means for mechanically connecting 20 said terminal members so as to relieve said fusible element of tension applied to the fuse link assembly, said connecting means including a strain wire connected to one of said terminal members and insulating means for connecting 25 said strain wire to the other of said terminals in spaced relation with respect thereto, so as to provide a gap between said strain wire and said terminal, which electrically separates same during normal operation of the fuse link assembly, bly and over which current passes during abnormal passage of current through the fuse link assembly, said insulating means including a pair 30

of spaced blocks secured to said terminal member at opposite sides thereof and provided with apertures through which said strain wire passes so as to provide a portion of the strain wire which is disposed in spaced alinement with the adjacent terminal to produce said gap, and a sleeve for attaching the strain wire to the other terminal member. 5

4. A fuse link assembly including a pair of spaced terminal members, a fusible element for 10 electrically connecting said terminal members, and connecting means for mechanically connecting said terminal members so as to relieve said fusible element of tension applied to the fuse link assembly, said connecting means including a strain wire connected to one of said terminal members and insulating means for connecting 15 said strain wire to the other of said terminal members in spaced relation with respect thereto, so as to provide a gap between said strain wire and said terminal member which electrically separates same during normal operation of the fuse link assembly and over which current passes during abnormal passage of current 20 through the fuse link assembly, said insulating means being secured to said terminal member and having the strain wire so associated and assembled therewith as to space a portion of the strain wire from the adjacent terminal member 25 to produce said gap. 30
